OTHER PUBLICATIONS

Display system utilizing permanently mounted pipes. 1502 Fabrics (Retail Store), High Point, North Carolina, believed by inventor to be used as early as 1975.

Declaration of Gary W. Loflin.

Prior Commercial Embodiment illustrated in sketch provided by Applicant; used, e.g. at 1502 Fabrics (Retail Store), High Point, North Carolina, believed by inventor to be used as early as 1981.

Primary Examiner—Brian N. Vinson
Attorney, Agent, or Firm—Allen, Dyer, Doppelt, Franjola & Milbrath, P.A.

[57] **CLAIM**

The ornamental design for a rack for displaying rolled goods, as shown and described.

DESCRIPTION

FIG. 1 is a front perspective view of the first embodiment of a rack for displaying rolled goods showing my new design; FIG. 2 is an enlarged top plan view of the left side portion thereof;

FIG. 3 is an enlarged front perspective view of the left side portion thereof;

FIG. 4 is an enlarged front perspective view of the second embodiment of a rack for displaying rolled goods showing my new design;

FIG. 5 is an enlarged top plan view of the end portion thereof, the individual components shown in various positions;

FIG. 6 is an enlarged elevational view of the end portion thereof, taken in the direction of the arrow 6 in FIG. 5; and,

FIG. 7 is an enlarged fragmentary perspective view showing the attachment of a horizontal member to a vertical member thereof.

The broken-line disclosures of walls, floor, ceilings, human figure, and rolled goods in the views are for illustrative purposes only and form no part of the claimed design.

1 Claim, 4 Drawing Sheets
